UNITED STATES PATENT OFFICE.

CHARLES N. HAZELTON, OF MORRISON, ILLINOIS.

ROLLING-CHAIR.

1,142,168.

Specification of Letters Patent. Patented June 8, 1915.

Application filed November 19, 1913. Serial No. 801,786.

To all whom it may concern:

Be it known that I, CHARLES N. HAZELTON, a citizen of the United States, residing at Morrison, in the county of Whiteside and

5 State of Illinois, have invented certain new and useful Improvements in Rolling-Chairs, of which the following is a specification.

My invention has reference to rolling chairs, of that kind which are used for invalids and infirm persons.

10 Machines of this class are usually constructed with reference to use either as a street vehicle or as a house chair, the machine in the first instance being provided

15 with rolling means whereby it can be propelled continuously in one direction so long as desired, while in the case of the house chair the rolling mechanism permits a quick turning of the vehicle to one side or the

20 other, either by the occupant of the chair or the attendant thereof. The house form of machine is necessarily inconvenient for use on the street by reason of its tendency to deviate from a straight course, while the

25 street form of chair is equally inconvenient to use in the house on account of the difficulty with which it can be turned from movement in a straight line.

In my device I provide a novel means 30 whereby the chair can be quickly converted from a house chair into a street chair, and the reverse, thus combining the most serviceable features of two distinct chairs in the one machine. The improvements in construction and arrangement of parts whereby this can be accomplished will more fully appear from the following specification, reference being had to the drawings accompanying the same, in which;

40 Figure 1 is a longitudinal section, centrally of a machine embodying my invention, looking toward the right hand side thereof. Fig. 2 is a cross-section through the front part of the platform 8 on the broken line $x-x$ of Fig. 1. Fig. 3 is a detail of the front part of the device, similar to Fig. 1, with the operating parts in a different position. Fig. 4 is an elevation showing the rear locking mechanism for the lever 45 15. Fig. 5 is a detail showing the rack 20 and forward locking means for said lever, in plan view.

There are a number of instances in which the parts referred to in the specification are 55 in duplicate in the machine, but only one of such parts is shown in the drawings,

such as the carrying-wheels, etc., and where such parts are referred to in the plural, both of the parts are intended, although one only is illustrated.

60

1 represents a seat-frame, suitably mounted on a pair of large carrying-wheels 2, provided on the outside with hand-rims 3. Connected with the frame 1 and extending rearwardly therefrom are handle-bars 4, united 65 by a handle 5 whereby the chair may be propelled by an attendant. The handle-bars are also provided with arm-rests 6, and supported on the seat-frame is a back 7.

70

8 is a platform, provided on its lower face with side-pieces 9, to the inner ends of which are connected supports 10, the upper ends of said supports being attached to the seat-frame 1. The platform is further supported by means of braces 11 and 12, connecting 75 said platform with the seat-frame. Mounted on the side-pieces 9 is an axle 13, provided on its ends with small carrying wheels 14, adapted to coöperate with the wheels 2 to cause the movement of the chair in a 80 straight line.

85

Pivoted on the inner face of one of the side-pieces 9 (preferably the right hand side piece) is a lever 15, the lower end of which is connected with a cross-piece 16, provided 90 on its lower face with a pair of swivel-rollers 17. The lever 15 passes upwardly through a slot 18 in the platform 8, and the opposite end of the cross-piece 16 is swingingly connected with the opposite side-piece 9 by means of a bracket 19. Connecting the support 10 and brace 11 is a bar 20, fixed to which at its forward end is a rack 21, the rear end of said rack being curved downwardly and attached to the platform 8. The 95 hand-lever 15 is capable of a reciprocating movement between said bar and rack to raise or lower the cross-piece 16. The lowering of such cross-piece operates to bring the swivel-wheels 17 in contact with the earth, 100 and raise the wheels 14 so that they cease to operate, as shown in Fig. 1. In this position the chair can be turned about within its own space by an attendant, or by the occupant of the chair through the use of the 105 hand-rims on the wheels. When the wheels 14 are in contact with the earth, as in Fig. 3, the machine is in condition for street use, and may be propelled along a side-walk or pavement in one continuous direction.

110

Near the forward end of the rack 21 is a catch 22, having a beveled face permitting

the forward movement of the lever 15 past such catch, such lever being constructed of metal possessing a slight degree of flexibility, and having an outward tension, so that in being forced forward the lever springs past the catch 22, and is then held thereby. To release the lever the upper part thereof is forced inwardly against the rack 21, whereupon the lever can be moved 10 rearwardly past the catch. Pivoted to the rear face of the support 10 is a latch 23, having a recessed arm 24 adapted to engage the lever 15 at the end of its rearward movement, and lock the same from accidental release. The shape of the arm 24 is such that in moving rearwardly and downwardly the lever forces such arm outwardly, and is automatically engaged thereby. Projecting outwardly from the latch 23 is an arm 25 15 which serves the double purpose of acting as a weight to hold the arm 24 normally in position to engage the lever 15, and also provides a convenient means for releasing the latch when it is desired to throw the lever 20 forwardly. When this latch is released the weight of the cross-piece 16 and apurtenant parts will cause such parts to drop downwardly, moving the lever 15 forwardly to a point where it can easily be reached by the 25 hand of the operator, to continue its movement.

It will be seen that the lever 15 is in a position to be conveniently operated either by the occupant of the chair or by an attendant thereof, and the latch 23 can also be conveniently actuated either from within or without the chair. The cross-piece 16 is preferably provided with two swivel-rollers so as to lessen the danger of the chair 30 35 setting when a person stands upon the platform 8 in getting into or out of the chair.

It will be obvious that the machine herein shown and described possesses all of the uses and advantages of two ordinary chairs 40 45 each having a separate function, and with very little additional construction.

My invention not only provides a chair which can be converted from one form to another as it is desired to use it in the house 50 or out of doors, but it is also susceptible of a double use in either case. For example, the occupant of the chair can be wheeled to a park, or other public place by an at-

tendant, the large and small carrying-wheels being used for that purpose, and then the 55 lever operated to bring the swivel rollers into use, whereupon the occupant of the chair can wheel or turn himself about at pleasure, by means of the hand-rims.

What I claim as my invention, and desire 60 to secure by Letters Patent of the United States, is:

1. A rolling chair, comprising a pair of large carrying-wheels; a seat-frame supported thereby; a pair of small carrying wheels rigidly united with said first-named wheels by said frame, normally operative, and adapted to act with said first-named wheels to propel said chair in a straight line; a cross-piece swingingly supported from said frame; swivel-rolling devices carried by said cross-piece; and means for actuating said cross-piece to bring said swivel-rolling devices in contact with the earth, and raise 65 70 75 said small carrying-wheels from operation therewith.

2. A rolling-chair, comprising a pair of large carrying-wheels; a seat-frame supported thereby; a platform rigidly supported from said seat-frame; a small pair of normally operative wheels fixed to said platform, and acting with said first-named wheels to propel said chair in a straight line; a cross-piece, swingingly supported from said platform; swivel-rolling devices 80 85 carried by said crosspiece; a hand-lever connected with said cross-piece and passing upwardly through said platform to a point convenient to the occupant of said chair, whereby said cross-piece may be operated to 90 bring said swivel-roller devices into contact with the earth, and raise said small carrying wheels from operation therewith; means for locking said lever in position with said swivel-roller devices in engagement with the 95 earth; and means for automatically locking said lever in position with said swivel-roller mechanism out of engagement with the earth.

In testimony whereof I affix my signature 100 in presence of two witnesses.

CHARLES N. HAZELTON.
